US00D630238S

(12) **United States Design Patent**
Fukuma et al.

(10) **Patent No.:** US D630,238 S
(45) **Date of Patent:** ** Jan. 4, 2011

(54) **CAMERA STAND**

(75) Inventors: **Yohei Fukuma**, Tokyo (JP); **Satoshi Masamitsu**, Tokyo (JP)

(73) Assignee: **Sony Corporation**, Tokyo (JP)

(**) Term: **14 Years**

(21) Appl. No.: **29/356,768**

(22) Filed: **Mar. 2, 2010**

(30) **Foreign Application Priority Data**

Oct. 5, 2009 (JP) D2009-023139

(51) **LOC (9) Cl.** **16-05**

(52) **U.S. Cl.** **D16/242**

(58) **Field of Classification Search** D13/107, D13/108; D16/208, 237, 242; 248/121, 248/122.1, 176.1, 187.1; 348/373; 396/419

See application file for complete search history.

(57) **CLAIM**

The ornamental design for a camera stand, as shown and described.

DESCRIPTION

FIG. 1 is a perspective view of a camera stand showing our new design;

FIG. 2 is a front elevational view, thereof;

FIG. 3 is a rear elevational view thereof;

FIG. 4 is a left side elevational view thereof;

FIG. 5 is a right side elevational view thereof; and,

FIG. 6 is a top plan view thereof.

Portions in broken lines are for illustrative purpose only and form no part of claimed design. The dot-dash broken lines define, but are not included in, the boundaries of the claimed design.

1 Claim, 4 Drawing Sheets

FIG. 1

FIG. 4

FIG. 5
